UNITED STATES PATENT OFFICE.

JOHN R. CUMMINGS, OF NEW YORK, N. Y., ASSIGNOR, BY MESNE ASSIGNMENTS,
TO THE AMERICAN PRESS ASSOCIATION, OF ILLINOIS.

CLAMPING DEVICE FOR STEREOTYPER'S CASTING-BOXES.

SPECIFICATION forming part of Letters Patent No. 433,448, dated August 5, 1890.

Application filed January 3, 1888. Serial No. 259,746. (No model.)

To all whom it may concern:

Be it known that I, JOHN R. CUMMINGS, of New York, New York county, and State of New York, have invented certain new and useful Improvements in Clamping Devices for Stereotypers' Casting-Boxes; of which the following is a full, clear, and exact description, reference being had to the accompanying drawings, and letters of reference marked thereon.

Heretofore when casting stereotype-plates, after the cover of the casting apparatus is closed onto the box, before the metal is poured into the same they have been clamped together by several individual hook-shaped clamps, which were pivoted to the box in such manner as to be capable of being oscillated transversely over the edge of the cover, in which position, by means of screws passing through the ends of the hooks and impinging against the upper surface of said cover, they clamped the box and cover together. This arrangement made it necessary for attention to be given to each clamp-hook, thus requiring considerable time and labor, and, besides, making it difficult to always obtain the same pressure between the edges of the cover and box at all points.

My invention is designed to avoid the necessity of any personal attention being given to the clamping devices at all, because the clamping devices operate automatically when the mold is oscillated from the horizontal position (in which position it is prepared for casting) to the vertical position, (in which position the metal is poured into it,) substantially as hereinafter fully described, and as illustrated in the drawings, in which—

Figure 1 is a longitudinal central section of my invention. Fig. 2 is a side elevation thereof. Fig. 3 is a view showing the back or under surface of the box. Fig. 4 is a side view of a modification of my invention. Fig. 5 shows a side elevation of a stereotype casting-box and cover, showing modified devices for throwing the bolts which lock the box and cover together. Fig. 6 shows a rear edge view of my invention with that part of the knuckles through which the pintle passes in cross-section, and Fig. 7 shows a detail view of the end of the pivotal shaft of the box.

Referring to the drawings, A represents the "box" of a stereotyper's mold, and B the "cover" thereof. The construction of the box and cover is the same as those in common and extensive use, and they are supported by and oscillated between the usual L-shaped frames C.

Instead of providing the box A with trunnions which are journaled in the open bearings in the ends of the shorter vertical portion c of frames C, I prefer to secure in said ends the transverse stationary shaft b, as shown in Fig. 7. This shaft passes through female bearings in the flanged sides of the box, and is preferably provided near its center of length with bosses d and e, whose peripheries are circular and whose centers are offset from the center of shaft b, the former d toward the front of the apparatus, and the latter c a corresponding distance toward the rear of the machine, diametrically opposite to each other.

Journalized on the bosses d and e are the inner ends of the links D and E, the former pursuing a longitudinal horizontal course to the front of the machine, where it is secured to the transverse bar F, and the latter pursuing a similar course to the rear, where it is secured to the transverse bar G. These bars F and G are removed a corresponding distance from the shaft b, with which they are parallel, and their ends extend through the longitudinally-elongated guide-holes f f in the side flanges of the box and have secured to them the bolts g g.

Bolts g g move in the guides or staples projecting from the sides of the box, as shown, and those secured to the end of the rear transverse bar G have their engaging ends 90 slightly tapering and pointing toward the front of the machine, whereas those secured to the ends of the forward transverse bar F have their engaging ends slightly tapering and pointing toward the rear of the machine. 95

Secured to or made integrant with the sides of the cover B, at such points that they are contiguous to but nearer the shaft b than the bolts g g, are the plates or lugs H. These plates H extend down laterally past the meeting edges of the cover, so that when said cover is closed upon the box they lap over

the sides thereof directly in front of the engaging-points of bolts *g*, and they have in their edges next said bolts notches or recesses *h h*, so located with reference to said bolts 5 that when said cover is closed upon the box and the bolts are shot simultaneously toward the center of length of the same they enter said notches and lock the box to the cover. I prefer to bevel the entrance to said notches 10 or recesses *h*, so that the bolts can enter easier, and so that the bolts can bring the box and cover closer together the farther they enter said notches.

When said casting apparatus or mold is in 15 a horizontal position, the bolts are at the limit of their throw away from the notched plates *H*. As the mold is oscillated to a vertical position preparatory to having the metal poured therein, the bolts are shot into the notches 20 according as the links assume the perpendicular position, or, in other words, according as they are thrown out of alignment with an imaginary straight line intersecting the centers of the eccentric bosses *d* and *e*, on which 25 their ends next shaft *b* are journaled. As these links are thrown into the vertical position, they draw the transverse bars *F* and *G* toward the center of length of the mold a distance corresponding to the difference be- 30 tween the radius of said links and the radius described from the center of shaft *b* to the bars *F* and *G* when the mold is in a horizontal position. When the mold is oscillated back to the horizontal position, the bolts are 35 pushed out of the notches in plates *H*. By exchanging the positions of the centers of the eccentric bosses *d* and *e* the bolts would be shot outward away from the centers of length of the mold. The plates *H* in this 40 event would be so situated that they would be nearer the ends of the mold, so as to be in register with the bolts when shot.

Instead of eccentric bosses *d e*, arms *k k* 45 may project horizontally from the shaft *b*, to the ends of which the links *D* and *E* are pivotally connected.

If desired, I can construct the box with trunnions in the usual manner, and instead of using the links *D* and *E* and transverse 50 bars *F* and *G* can use two links on each side of the box. The inner end of these links *K K* would be pivoted on lugs projecting from the side of the shorter vertical end *c* of the frames *C*, in positions intersected by trans- 55 verse horizontal lines passing through the center of the trunnions. These links would extend alongside of the sides of the mold, and would be pivotally secured direct to the bolts. The mold being turned to a vertical position, 60 the same action of the bolts will follow with this construction as with that heretofore explained.

While I prefer the stationary transverse

shaft *b*, yet I could, as shown in Fig. 5, make a shaft *r*, that could be oscillated by means 65 of a crank *v* independently of the mold. In this event, however, I would have to secure ratchets *s* upon the shaft just outside of the bearings of the box and pivotally secure pawls *t* to the side of said box, which would engage 70 the ratchet and prevent said shaft from independently revolving back to its normal position when the power which was exerted to turn it was released therefrom. With this construction the shaft would oscillate with the 75 mold when the latter was tilted to the perpendicular position.

In order to use my improved mold for both plate and type-high casting, I prefer, as shown in Fig. 6, to use an eccentric pintle *L*, passing 80 through the knuckles *m m* of the box and *n n* of the cover, which, when turned so that the offset portion on which the knuckles *n n* of the cover are pivoted will be above the center of the pintle itself, will separate the 85 edges of the box and cover, so that the type-high gages *o o* can be placed between the same. I also, in this event, provide each of the plates *H* with two notches instead of one—one for the plate-high casting and the other 90 to be engaged by the bolts for the type-high casting.

What I claim is—

1. In a stereotyper's casting apparatus, the combination, with the cover having notched 95 plates secured to the longitudinal sides thereof, of the tilting box, to one end of which said cover is hinged, the reciprocating bolts, and the links for operating said bolts having their ends farthest from said bolts pivoted eccentric to the tilting center of said box, as set forth.

2. In a stereotyper's casting-box, the combination, with the cover and notched plates secured near the ends of each side thereof, 105 of the box, bolts, transverse reciprocating bars, the ends of which project through longitudinally-elongated apertures in the side flanges of said box, and the links connected at one end to said bars and having their opposite 110 ends pivoted eccentrically to the transverse stationary shaft upon which said casting-box oscillates, as set forth.

3. In a stereotyper's casting-box, the combination, with the cover and notched plates 115 secured near the ends of each side thereof, of the box, bolts, transverse reciprocating bars, links, and transverse stationary pivotal shaft, said shaft being provided with eccentric offsets, upon which the inner contiguous 120 ends of said links are journaled, as and for the purpose set forth.

JOHN R. CUMMINGS.

In presence of—

PORTER B. COOLIDGE,
FRANK D. THOMASON.
